ROUGH ROUNDING MACHINE

Corwin W. Baker, Beverly, Mass., assignor to
 United Shoe Machinery Corporation, Flemington, N. J., a corporation of New Jersey

Application December 29, 1947, Serial No. 794,258.

10 Claims. (Cl. 12—18)

1
 This invention relates to machines for rough rounding shoe soles, the illustrated machine being similar to that disclosed in Letters Patent 1,030,606 granted on June 25, 1912, upon an application of F. H. Perry, but having a forepart and crease guide mechanism of the type disclosed in my prior application Serial No. 652,721 filed on March 7, 1946. More particularly, the present invention is concerned with improved means for operating the forepart guide in a machine of this type.

As is well understood by those familiar with this type of machine and its operation, a shoe is under the control of the crease guide during the first and last parts of a rough rounding operation while the shank portion of the shoe is being operated upon, and is under the control of the forepart guide while the forepart of the shoe is being rounded. The forepart guide is moved into and out of operative position by mechanism including a treadle which is held down by the operator throughout the period during which the shoe is under the control of the forepart guide; and through connections between the forepart guide and crease guide the latter is moved into and out of its operative position in alternation with the forepart guide.

The forepart guide in the machine of my prior application referred to above comprises a cam-like member against which the shoe slides at certain times. At such times this member, although it is mounted to rotate, is locked against rotation by a releasable latch. When in rounding the forepart, it is desired to vary the sole-edge extension, this latch is released whereby the cam-like member is permitted to rotate in response to feeding movement of the shoe, and the eccentricity of the cam-like member causes the shoe to be moved heightwise relatively to the knife whereby the desired variation in the extension is made. This type of mechanism by which the forepart extension is varied is commonly called a "Baltimore attachment," and the above-mentioned Perry machine comprises such an attachment although it is different structurally from that briefly described above. However, it is true of both the machines referred to, and of this type of machine generally, that the operator is required, while holding down the treadle which operates the forepart guide, to actuate another member, usually a knee pad, to start the operation of the Baltimore attachment.

The above-mentioned treadle and knee pad are operated by the operator's left foot and leg, respectively. It is evident, therefore, that the op-

erator's weight is supported for the most part by his right leg and that his body will sway slightly from side to side, in maintaining his balance, depending upon the action required of the left leg in operating the treadle and knee pad. This operation of the treadle and knee pad is fatiguing to the operator, and, to the extent that it disturbs his balance, makes it the more difficult for the operator to turn the shoe so that the trimmed edge of the sole is always horizontal at the knife. Moreover, the operator's fatigue is detrimental not only to his production but also to the quality of his work, since it tends to result in erratic timing of the operation of the treadle and knee pad.

In view of the foregoing, it is a principal object of the invention to provide an improved rounding machine in the operation of which the physical exertion required of the operator, in connection with the operation of the forepart guide and Baltimore attachment, is reduced to a minimum so that he can give more attention than formerly to the guiding of the shoe, and to the timing of the operation of the forepart guide and Baltimore attachment.

To this end, and in accordance with one feature of the invention, the illustrated machine is provided with power operated means for moving the forepart guide into and out of operative position, each of such movements being initiated by only a momentary actuation by the operator of an operator controlled member which responds to a very slight pressure. This power operated means is constructed and arranged to operate in different stages, one for each movement of the forepart guide, each stage of its operation being initiated by the operator and then automatically continued and stopped. In another stage of its operation, intermediate between those referred to above and initiated by another momentary actuation of the same operator controlled member, this means is also constructed and arranged to release the latch of the Baltimore attachment while continuing to hold the forepart guide in its operative position.

It is now evident that the above-described mechanism in the illustrated machine relieves the operator of the former practice of holding down for an extended period the treadle for operating the forepart guide. In fact, each movement of the forepart guide and the operation of the Baltimore attachment is initiated by the momentary operation of only one operator controlled member under knee pressure so light that

the operator's position and balance are not disturbed.

In both a right and left shoe there is an abrupt change in the sole edge extension at the junction of the inside shank with the forepart, and a gradual change at the junction of the outside shank with the forepart. Therefore, in operating on either a right or left shoe two changes in the control of the shoe by the forepart and crease guides occur, the change at the inside of the shoe being made abruptly and that at the outside being made gradually. With respect to each shoe, the first change occurs upon moving the forepart guide into its operative position, and the second upon moving this guide out of its operative position. Accordingly, the power operated means for operating the forepart guide in the illustrated machine is constructed and arranged, in accordance with another feature of the invention, to move the guide into and out of operative position at different rates. The foregoing paragraph deals with the operation on the forepart guide in connection with the rounding of one shoe. The operation of the forepart guide will now be considered with reference to its movement involved in operating upon successive shoes.

It is usual for the rounding operation to be carried out upon right and left shoes alternately, this being consistent with the general practice of regarding a run of shoes in terms of pairs throughout their manufacture, to insure the proper matching of the shoes of each pair. On a right shoe the rounding cut is started at the inside and proceeds toward the outside thereof; and on a left shoe it is made in the opposite direction. Again having in mind the similar positions of the abrupt and gradual changes in the extension in right and left shoes, it is now evident that the order in which the abrupt and gradual changes in control of the shoe occur is reversed from one shoe to the next. Accordingly, the means for operating the forepart gage in the illustrated machine is further so constructed and arranged, in accordance with another feature of the invention, that successive movements of the forepart guide in the same direction occur at different rates.

It will now be apparent that the movements of the forepart guide, although different in rate, take place at predetermined rates and during predetermined periods of time. These features insure uniformity in the rounding operation as between the shoes of a pair as well as in an entire run of shoes, since the operator is enabled to anticipate accurately the time when the operation of the power operated means for operating the forepart guide must be initiated in order that any movement of the guide will be carried out at the proper time.

In accordance with another feature of the invention the means for operating the forepart guide, as herein illustrated, comprises a cam which is so shaped and arranged as to provide the desired sequence, direction, and rate of all movements of the guide as stated above. Invention is also to be recognized in novel control means for starting and stopping the operation of the cam, once for each stage of its operation.

These and other features of the invention will now be further described in the following specification and will be pointed out in the appended claims.

In the drawings,

Fig. 1 is a side elevation of an illustrative machine embodying the invention;

Fig. 2 is an enlarged side elevation of a part of the head of the machine and showing its principal operating members and work guides;

Fig. 3 is a front elevation showing only the forepart guide of Fig. 2 and as viewed perpendicularly thereto;

Fig. 4 is a front elevation of part of the power-operated means for operating the forepart guide;

Fig. 5 is a sectional side elevation of a part of the mechanism of Fig. 4, the section being taken along the line V—V in that figure;

Fig. 6 is a fragmentary plan view of a switch and operating means therefor, the switch being shown in dotted lines in Fig. 4 and being a part of the operating means for the latch of the forepart guide;

Fig. 7 is a fragmentary sectional front elevation of a part of the operating means for the switch which starts and stops the operation of the structure illustrated in Fig. 4, the section being taken along the line VII—VII in Fig. 5;

Fig. 8 is a diagrammatical view illustrating the use and operation of the forepart guide during a rounding operation upon a right shoe;

Fig. 9 is a view similar to Fig. 8 but pertaining to a rounding operation upon a left shoe;

Fig. 10 is a diagrammatical view indicating the positions of the cam for operating the forepart guide and of the switch operating cam at the beginning and end of each stage of their operation during a rounding operation upon a right shoe; and

Fig. 11 is a diagrammatical view similar to Fig. 10 but pertaining to a rounding operation upon a left shoe.

The illustrated machine comprises a base 10 (Fig. 1) upon and above which there is mounted an operating head 12, similar to that of the machine disclosed in the above-mentioned Perry patent, and having as its principal operating members a bottom rest 14, an anvil 16 and a knife 18. The sole edge of a shoe to be rounded is received between the bottom rest 14 and the anvil 16, these members being oscillated to and fro to feed the work, such feeding movement occurring when the bottom rest and anvil swing together toward the left (the machine being viewed from the operator's station in front of the machine). During the backward stroke of the anvil 16 its movement is momentarily interrupted, at which time the knife 18 cuts through the sole against the anvil. While the knife is in the work the bottom rest 14 is moved backwardly and during this time a channel is cut in the work by a knife carried by the bottom rest. The above briefly describes the cutting and feeding action of the machine, a more complete understanding of which, as well as of the construction and operation of the above-mentioned principal members of the machine, may be obtained from the Perry patent.

In order to determine the distance from the upper at which the sole edge is trimmed, i. e., the sole edge extension, the position of the shoe heightwise of the knife 18 is controlled and varied at different times by either a crease guide 20 or a forepart guide 22. These guides as illustrated herein, and the mechanism which connects them, are similar to the corresponding structure of the machines disclosed in my above-mentioned application and another application Serial No. 779,378, filed on October 11, 1947, also in my name.

As is well understood in this art, the crease guide 20 controls the shoe when the knife is operating at the inner and outer shank portions of the shoe; and the forepart guide 22 controls the shoe while the knife is operating around the forepart. The forepart guide 22 is carried by a lever 24, which, through connections between it and another lever 26, is swung in a clockwise direction to lower the forepart guide 22 into its operative position. During such movement of the forepart guide the crease guide 20 is raised, first gradually and then abruptly, out of its operative position, this movement of the crease guide occurring at a predetermined time and rate and being under the control of mechanism including an abutment roll 28 and a cam 30 engaging the roll. This cam is mounted upon a lever 32 to which the crease guide 20 is attached. A spring 34 is tensioned in response to downward movement of the forepart guide 22, and assists in elevating the forepart guide, both movements of which are derived from power-operated mechanism for operating the lever 26. As the forepart guide 22 rises, incident to transferring control of the shoe to the crease guide 20, the latter is abruptly brought near to its operating position and then is gradually lowered into its operative position. It is during this latter movement of the crease guide that the control of the shoe is transferred to it from the forepart guide.

The forepart guide 22 illustrated herein is similar to, but a simplification of, the forepart guide disclosed in my above-mentioned prior application Serial No. 652,721. It will be described below briefly, however, in order to facilitate the description to follow of its relation to the means for operating it, with which the invention is particularly concerned. Extending upwardly from the lever 24 (Fig. 2) is a projection 36 to the opposite sides of which are fixed plates 38. The projection and plates form a slideway for a slide 40 from which extends downwardly an arm 42, at the lower end of which the body 44 of the forepart guide is rotatably mounted upon a stud 46 fixed to the arm. The guide body has a central guide member 48 integral therewith and carries, one at each side of the central guide member, a leading guide member 50 and a trailing guide member 52. All three guide members can be adjusted together, heightwise of the knife 18, by turning a thumb screw 54 which is threaded into the upper end of the slide 40 and bears against the upper end of the projection 36. A spring 56 coiled around the screw 54 and interposed between the slide 40 and projection 36 urges the slide downwardly, holding the screw seated on the projection. The slide is clamped in adjusted position by setting up a thumb screw 58 which is threaded into the projection 36 and extends through an elongated slot 60 in the slide, the slot being arranged to permit the desired adjustment of the slide. The leading and trailing guide members 50, 52 are mounted for angular adjustment on the guide body 44 and swing for this purpose about axes at their inner ends adjacent to the central guide member 48. Each of the guide members 50, 52 is fixed to an arcuate dovetail slide 62 which is adapted to move in a slideway 64, shaped concentric with the inner end of the associated guide member, in a wing 66, one extending from the guide body 44 at each side thereof adjacent to the guide member 48. Each slide has pivoted thereto a link 68 which is pivoted to the upper arm of a bell crank lever 70, each lever being pivotally mounted upon the guide body 44 on a

screw 72. The lower arms of the bell crank levers 70 ride in a channel in a block 74 which is arranged to slide radially of the guide body in a slot 76 formed therein. A thumb screw 78 threaded into the block 74 and bearing against the front face of the guide body is arranged to clamp the block in adjusted position. It is now evident that by adjusting the block in its slot the guide members 50, 52 are simultaneously adjusted by equal amounts. The effect of this adjustment is to vary the eccentricity of the guide members 50, 52, it being understood that their outer ends will usually, if not always, be nearer to the axis of the stud 46 than their inner adjacent ends as indicated by the arcs in broken lines (Fig. 3) drawn on the radius of the central guiding member 48.

Like my prior forepart guide, the present one is constructed so that it is locked against rotation about the stud 46 in its initial and central positions by a latch 80, the latch also being arranged to prevent the guide from being moved beyond its final position. When the guide is in its central position the latch is received in a recess 82 formed in the guide body 44, the central guide member 48 being directly below the stud 46 at this time. The latch slides vertically in a recess 84 formed in the slide 40. The recess 84 also receives a spring 86 which urges the latch toward the guide body 44. The latch 80 can be moved away from the guide body by the lower arm of a bell crank lever 88 which is pivoted by means of a screw 90 on the lever 24. This bell crank lever is operated, as will be described later, by a solenoid 92 the plunger 94 of which is connected to the bell crank lever by a link 96, the outer end of the link having a slot 98 which receives a pin 100 carried by the lever. A spring 99 stretched between the plunger 94 and the projection 36 causes the lever 88 to be normally held out of engagement with the latch 80. With the forepart guide in its initial position the leading guide member 50 at 102 is down, directly underneath the axis of the stud 46. The guide is releasably held in this position by the latch 80 which is adapted to be received in a recess 104 in a stop 106 which is mounted on the guide body 44 for adjustment about its periphery. This stop is slotted to receive a set screw 108 threaded into the guide body 50 and by which the stop can be clamped in any adjusted position. Another similar stop 110, having a shoulder 112 adapted to be engaged by one side of the latch 80, determines the final position of the guide. The stop 110 is also mounted for adjustment about the periphery of the gage body 44 and is adapted to be clamped thereto by a set screw 114. A spring 115 mounted in an annular channel 116 in the guide body 44 resists clockwise turning of the forepart guide, and returns the gage from its final position to its initial position when the gage is released near the completion of a rounding operation upon a left shoe as will be described below. This spring is stretched between two pins, one pin 117 being fixed to the arm 42 and the other being fixed to the guide body 44.

Before proceeding with the description of the mechanism for operating the forepart gage, the use and operation of the machine will next be described with reference to the rough rounding of the right and left shoes of a pair which is illustrated diagrammatically in Figs. 8 and 9.

This operation upon a right shoe is begun near the inside heel breast line approximately at 118 (Fig. 8a), the shoe at this time being under the

control of the crease guide 20. The shoe is fed by the machine toward the left and the operator turns the shoe throughout its feeding movement so that the trimmed edge at the point of operation of the knife is always horizontal. By the time the operation has proceeded about to the inside ball line the shoe will have the position illustrated in Fig. 8a, the forepart guide 22 being raised and in its initial position, that is, swung to the extreme of its counterclockwise rotation, 10 the latch 80 holding it in this position by engagement with the stop 106. At this time it is desired that the control of the shoe be transferred from the crease guide to the forepart guide and, accordingly, the forepart guide is lowered into engagement with the shoe at 120, the crease guide being simultaneously retracted. This transfer of the control of the shoe from one guide to the other is carried out without interrupting the feeding movement of the shoe.

As the rounding of the forepart proceeds, the shoe is turned as required by its changing contour, the shoe also being held against the leading guide member 50 against which the shoe slides until the point of operation of the knife approaches the outside tip line. At this point, such as approximately at 122 (Fig. 8b), the latch 80 is released, whereupon with further feeding movement of the shoe the gage member 50 rolls upon the shoe, freely rotating about the stud 46. Since the effective radius or eccentricity of the guide member 50 gradually increases as the point of its engagement with the shoe approaches the central guide member 48, the sole edge extension will be gradually increased because the shoe is being moved downwardly away from the knife. When the point of operation of the knife reaches the vicinity of the outside ball line as at 123 the latch 80 is received within the notch 82 and rotation of the forepart guide is stopped. The guide is now in its central position which causes the maximum sole extension to be formed upon the shoe. The shoe now slides on the central guide member 48, and as the point of operation of the tool goes into the outside shank, the crease guide 20 is gradually brought into engagement with the shoe while the forepart guide is gradually moved away from the shoe as at 124 (Fig. 8c). The rounding cut is now continued with the shoe under the control of the crease guide and is completed at the outer heel breast line as at 125.

In this manner is the variable sole edge extension formed upon the shoe, it being relatively narrow at the shank at each side thereof, and wider around the forepart, there also being smooth transitions between the different extensions where the changes in them occur. It is further apparent that the forepart extension reaches a maximum in the vicinity of the outside ball line, and that the extension gradually increases from a lesser extension toward this maximum from each side thereof. This style of edge is commonly called a "Baltimore" edge, and it is therefore appropriate to refer to the illustrated forepart guide as a Baltimore attachment since its rotatable mounting on the stud 46 and the eccentricity of its guiding members 50 and 52 produce such an edge.

In operating upon a left shoe the operation is started at the outside heel breast line approximately at 126 (Fig. 9a), the shoe being under the control of the crease guide 20. As the point of operation of the knife approaches the outside ball line the forepart guide is lowered into engagement with the shoe as at 128, the crease guide

being gradually retracted from the shoe at the same time. When the forepart guide first engages the left shoe its central guide member 48 is used, the shoe being slid against this guide member until the point where the extension is to be the maximum is brought to the knife. At this point, for example, at 130 (Fig. 9b), the latch 80 is released and as the feeding of the shoe proceeds the trailing guide member 52 rolls on the shoe, the guide member rotating freely about the stud 46 until the shoulder 112 on the stop 110 engages the latch 80. At this time, a point on the sole edge near the outside tip line, as at 132, will have been brought to the knife, and from this point the shoe is slid in engagement with the outer end of the trailing guide member 52 until a point near the inner ball line has been brought to the knife. At this point, as at 134 (Fig. 9c), the forepart guide is raised from the shoe and the crease guide is lowered to take over the control of the shoe. As soon as the forepart guide leaves contact with the shoe, it is automatically swung about the stud 46 into its initial position again, in which the point 102 on the leading guide member 50 is directly below the stud 46. With the shoe now under the control of the crease guide the rounding operation is continued throughout the inside shank until the inside heel breast line at 136 is reached.

The following is a description of the means for operating the forepart guide in the above manner, with which is combined a statement of the operation of this means during the rounding of the right and left shoes of a pair.

The above-mentioned lever 26 for operating the forepart guide 22 is connected at its outer end to a rod 137 which corresponds to the rod 43 of the prior Perry machine. The rod 137 is power operated by mechanism comprising a lever 138 having rotatably mounted on its lower end a roll 139 adapted to engage the periphery of a cam 140. The outer end of the lever 138 carries an eyebolt 142 which bears against a collar 144 adapted to be adjusted along and fixed to the rod 137. The lever 138 is mounted to swing vertically on a stud 146 which is threaded into a boss on the base 10. The cam 140 is mounted to rotate in a bracket 148 which is secured to a base plate 150, the latter being fixed to the base 10 of the machine. Associated with the cam 140 is a clutch element 152 into and out of engagement with which a second clutch element 154 is adapted to slide, the element 154 being splined to a drive shaft 156 which constantly rotates when the machine is in operation. This drive shaft extends from a gear reduction unit 158 which is fixed to the base plate 150 and which receives power through a pulley 160 over which runs a belt 162, the belt being driven by a motor-pulley 164.

The clutch element 154 is operated to start and stop the rotation of the cam 140 by mechanism including a lever 166 which is pivoted at 168 to a bracket 170 secured to the base plate 150. The lower end of the lever 166 carries a pin 172 which is received in a slot 174 in a link 176 which is pivoted by means of a screw 171 to the plunger 178 of a solenoid 180. This solenoid is energized, to cause the clutch elements to be engaged, by the closing of a switch 182 which is connected in series with the solenoid and a source of power. When the switch is opened the clutch elements are disengaged by the action of a tension spring 184 which is stretched between a stud 186 fixed to the bottom of the base plate 150 and the screw 175 177.

The switch 182 is closed in response to an inward movement of a knee pad 188 which is mounted on a member 190 at a height convenient to be engaged by the operator's knee. This member is pivotally mounted to a swing with a parallel motion upon a link 192 and the upper arm of a bell crank lever 194, the link being rotatably mounted on the above-mentioned stud 146. The bell crank lever 194 is mounted to rotate on a stud 196 which is threaded into a boss on the base 10. Movement of the member 190 is limited by a screw 197 which is threaded into the base 10 and is adapted to be engaged by shoulders at the opposite ends of a recess formed in the member. In the lower arm of the lever 194 is fixed a pin 198 which overlies another pin 200 fixed to the upper arm of a bell crank 202 which is mounted to swing on the stud 196. Secured to the lever 202 by means of the pin 200 is a finger 204 the upper end of which is bent over a plunger 206 by which the switch 182 is operated. The switch is fixed to an angle iron 208 which is mounted on the studs 146 and 196.

Let it now be assumed that a right shoe is to be rounded, that the forepart guide 22 is in its elevated inoperative position, and that the cam 140 is in the position illustrated in Figs. 1, 5, and 10a. The operator presents the shoe to the machine and rounds the inside shank from the starting point at 118 (Fig. 8a) with the shoe under the control of the crease guide 20. When the point of operation of the tool reaches the point where the control of the shoe is to be transferred to the forepart guide, as at 120, the operator presses upon the knee pad 188, which, through the connections described above, causes the switch 182 to be closed and the rotation of the cam 140 (counter-clockwise, Fig. 5) to be started. An abruptly rising slope 210 on the cam in passing the roll 139 causes the rod 137 to be lowered and the forepart guide 22 to be quickly brought into operative position. The switch 182 is automatically held closed, immediately after it is first closed by the operator, by a cam surface 212 on a cam 214 which is fixed to the inner side of the cam 140. The cam surface 212 is adapted to bear against a roll 216 which is rotatably mounted on the lower arm of the lever 202. A spring 215 is stretched between the lower ends of the levers 138 and 202 and holds their rolls 139, 216 in engagement with the cams 140 and 214, respectively. Thus, once the machine has been started by a momentary operation of the knee pad 188, the cam 140 continues to rotate until the rising slope 210 has passed beyond the roll 139. At this time, a recess 218 in the cam 214 permits the bell crank 202 to swing in a clockwise direction under the influence of the spring 215 whereby the switch plunger 206 is released by the finger 204 and the circuit for the solenoid 180 is opened. The clutch elements 152, 154 are now disengaged and the cam 140 is stopped in the position illustrated in Fig. 10b. With the cam 140 in this position the rounding operation on the right shoe is continued, the shoe being slid against the outer end of the leading guide member 50 until the operation has reached the stage indicated in Fig. 8b. It is now time for the gradual increase in the forepart extension to begin and, accordingly, the operator actuates the knee pad 188 again to effect this result. A second stage in the rotation of the cam 140 is thus begun, the switch 182 being held close by a cam face 220 on the cam 214 and the forepart guide 22 being held in its operative position by a concentric cam face 222 on the cam 140. Shortly after this second stage of the rota-

tion of the cam 140 begins, a small lug 224 (Figs. 5 and 6) on the outer side of the cam 140 engages and depresses the plunger 226 (Figs. 4 and 6) of a switch 228 which is electrically connected in series with the above mentioned solenoid 92 for operating the latch 80 of the forepart guide. The switch 228 is secured to a bracket 230 which is fixed to the base plate 150, the switch being so located that its plunger is at the same height as the axis of the cam 140 and in the path of the lug 224. As has been previously described, when the solenoid 92 is energized the latch 80 is retracted from the recess 82 in the body 44 of the forepart guide permitting the leading guide member 50 to roll on the shoe in response to feeding movement thereof. The second stage in the operation of the cam 140 is terminated when a recess 232 in the cam 214 comes opposite to the roll 216 whereby the lever 202 is again permitted to swing in a clockwise direction to open the switch 182. At this time the cam 140 will have been moved to bring the end of the concentric cam face 222 near to the roll 139 (Fig. 10c).

When the rounding operation has proceeded to the point indicated by Fig. 8c, and it is desired to transfer the control of the shoe from the forepart guide to the crease guide, the operator again strikes the knee pad 188, starting the third stage of operation of the cam 140. During this stage of its operation a gradually falling slope 234 on the cam 140 is moved past the roll 139 whereby the forepart guide 22 is permitted slowly to rise out of operative position. The operation of the cam 140 in this stage is maintained by the action of a concentric cam face 236 on the cam 214 and is terminated when a recess 238 comes opposite to the roll 216. With the crease guide 20 now in control of the shoe the rounding of the right shoe is completed at the outside shank. It will now be observed that the cam 140 is so designed as to move the forepart guide abruptly into its operative position during an operation upon a right shoe, and that the guide is retracted from this shoe gradually at a different slower speed. Thus, the abrupt and gradual changes in the control of the shoe by the guides are effected where the changes in the sole edge extension are abrupt and gradual, respectively.

Moreover, during the stage of operation of the cam 140 intermediate between those which cause the guide 22 to be moved into and out of operative position, the guide is held in its operative position and its latch is released to permit the rotation of the guide which produces the gradual increase in extension up to the maximum.

Considering now the rounding of a left shoe, the cut is begun near the outside heel breast line, as at 126 (Fig. 9a), the shoe being under the control of the crease guide 20 until the point of operation of the knife approaches the junction of the shank and forepart. When the control of the shoe by the crease guide is to be transferred to the forepart guide, as at 128 (Fig. 9a) the knee pad 188 is actuated again to start the rotation of the cam 140. During this first stage of its operation during the rounding of a left shoe a gradually rising cam face 240 (Fig. 11a) passes the roll 139 and causes the forepart guide 22 gradually to be lowered into engagement with the shoe. The switch 182 is held closed throughout this stage of operation of the cam 140 by the action of a concentric cam surface 242 on the cam 214 which engages the roll 216. This stage of the operation of the cam 140 is terminated when a recess 244

comes opposite to the roll 216, as illustrated in Fig. 11b, and the switch 182 is opened again.

With the shoe now in engagement with the center guiding member 48 it is fed past the tool, sliding on this guiding member, until a point as at 130 (Fig. 9b) near the outer ball line is reached, where a gradual decrease in the extension is to begin. At this point the knee pad 188 is again actuated to start another stage in the operation of the cam 140 during which the forepart guide is held in its operative position by a concentric cam face 248 on the cam 140. Shortly after this stage of operation of the cam 140 begins, a second lug 248 on the outer side of the cam strikes the plunger 226 of the switch 228 thereby closing the circuit to the solenoid 92 which causes the latch 80 to be retracted from the recess 82. The operation of the cam 140 is maintained throughout this stage by a concentric cam surface 249 on the cam 214 and is terminated when the roll 216 falls into a recess 250 in the same cam, as illustrated in Fig. 11c. Upon the release of the latch 80 in the above described manner, and with further feeding movement of the shoe, the trailing guiding member 52 rolls on the shoe causing the sole edge extension to be gradually diminished until the latch engages the shoulder 112 on the stop 110. At this time a point on the trailing guide member 52, as at 252, is directly below the stud 46 and engages the shoe at 132 (Fig. 9b). After the rotation of the guide member 52 has thus been stopped, the shoe is slid against the guide member to advance the cut around the forepart substantially to the inner ball line as at 134 (Fig. 10c). At this point by again operating the knee pad 188 the final stage of operation of the cam 140 is started during which an abruptly falling cam surface 254 on the cam 140 moves past the roll 139, permitting the rod 137 and hence the forepart guide 22 to rise rapidly. This final stage of operation of the cam 140 is continued by a concentric cam surface 256 on the cam 214 and is terminated when the roll 216 falls into a recess 258 in the cam 214 as illustrated in Fig. 11d.

It will now be observed that during the rounding operation upon a left shoe the forepart guide is moved into operative position gradually, rather than abruptly as in the case of the right shoe, the guide also being moved abruptly out of operative position when control of the shoe is taken over by the crease guide. Such operation of the forepart guide is consistent with the fact that in operating upon a left shoe the gradual and abrupt changes in extension are made in that order, the reverse of the order in which they occur in operating upon a right shoe.

Briefly to summarize the operation of the illustrated machine, in operating upon a right shoe the operator operates the knee pad 188 momentarily three times to initiate different stages of the operation of the cam 140. In the first stage the forepart guide 22 is moved abruptly into operative position to take over the control of the shoe from the crease guide. In the second stage, during which the forepart guide is held in its operative position, the latch 82 is released permitting rotation of the forepart guide for the purpose of causing the extension to be increased gradually to the maximum. In the third stage, the forepart guide is gradually moved out of its operative position giving over the control of the shoe to the crease guide 20. Thus during the operation upon a right shoe, the cam 140 moves through a half-revolution in three stages, its operation in each stage being automatically con-

tinued and terminated by the cam 214 and the mechanism operated thereby.

Similarly in operating upon a left shoe, the knee pad 188 is momentarily actuated, first, to cause the forepart guide 22 gradually to take over the control of the shoe from the crease guide; second, to release the latch 82 whereby the extension is gradually diminished from the maximum; and third, to cause the forepart guide to be abruptly moved out of operative position whereby control of the shoe is given over to the crease guide again. As before, once each stage of operation of the cam 140 is initiated it is automatically continued and terminated under the control of the cam 214.

Having thus described my invention, what I claim as new and desire to secure by Letters Patent of the United States is:

1. In a rounding machine, with a rounding tool and a guide for positioning a shoe relatively to the tool, said guide being mounted for movement into and out of operative position, in combination, power operated mechanism for advancing said guide into and retracting it from its operative position, operator controlled means for starting the operation of said mechanism, and means for stopping said mechanism when said guide reaches the end of each of its movements.

2. In a rounding machine, with a rounding tool and a guide for positioning a shoe relatively to the tool, said guide being mounted for movement into and out of operative position, in combination, power operated mechanism for advancing said guide into its operative position at one speed and for retracting said guide from its operative position at another speed, operator controlled means for starting the operation of said mechanism, and means for stopping said mechanism when said guide reaches the end of each of its movements.

3. In a rounding machine, with a rounding tool and a guide for positioning a shoe relatively to the tool, said guide being mounted for movement into and out of operative position, in combination, power operated mechanism for alternately advancing said guide into and retracting it from its operative position, said mechanism being constructed and arranged to cause successive movements of said guide in the same direction to occur at different speeds, operator controlled means for starting the operation of said mechanism, and means for stopping said mechanism at the end of each movement of said guide.

4. In a rounding machine, with a rounding tool and a guide for positioning a shoe relatively to the tool, said guide being mounted for movement into and out of operative position, in combination, power operated mechanism for alternately advancing said guide into and retracting it from its operative position at different speeds, said mechanism also being constructed and arranged to cause successive movements of said guide in the same direction to occur at different speeds, operator controlled means for starting the operation of said mechanism, and means for stopping said mechanism at the end of each movement of said guide.

5. In a rounding machine, with a rounding tool and a guide for positioning a shoe relatively to the tool, said guide being mounted for movement into and out of operative position, in combination, power operated mechanism for advancing said guide into and retracting it from its operative position, operator controlled means for starting the operation of said mechanism, and means for stopping said mechanism at the end of each movement of said guide.

6. In a rounding machine, with a rounding tool and a guide for positioning a shoe relatively to the tool, said guide being mounted for movement into and out of operative position, in combination, power operated mechanism for advancing said guide into and retracting it from its operative position at different speeds, said mechanism also being constructed and arranged to cause successive movements of said guide in the same direction to occur at different speeds, operator controlled means for starting the operation of said mechanism, and means for stopping said mechanism at the end of each movement of said guide.

7. In a rounding machine, with a rounding tool and a guide for positioning a shoe relatively to the tool, said guide being mounted for movement into and out of operative position, in combination, power operated mechanism for advancing said guide into and retracting it from its operative position, operator controlled means for starting the operation of said mechanism, and means for stopping said mechanism at the end of each movement of said guide.

8. In a rounding machine, with a rounding tool and a guide for positioning a shoe relatively to the tool, said guide being mounted for movement into and out of operative position, in combination, power operated mechanism for advancing said guide into and retracting it from its operative position, operator controlled means for starting the operation of said mechanism, and means for stopping said mechanism at the end of each movement of said guide.

for stopping said mechanism when said guide reaches the end of each of its movements, said mechanism comprising a rotatable cam having a slope which rises at one rate from a predetermined level and a second slope which falls at another rate toward said level whereby the movements of said guide into and out of operative position occur at different speeds.

6. In a rounding machine, with a rounding tool and a guide for positioning a shoe relatively to the tool, said guide being mounted for movement into and out of operative position, in combination, power operated mechanism for advancing said guide into and retracting it from its operative position, operator controlled means for starting the operation of said mechanism, and means for stopping said mechanism when said guide reaches the end of each of its movements, said mechanism comprising a rotatable cam having a pair of spaced slopes which rise at different rates and a second pair of slopes which fall at different rates, the slopes of each pair being contiguous to the slopes of the other at their lower levels, whereby successive movements of said guide in either direction occur at different rates.

7. In a rounding machine, with a rounding tool and a guide for positioning a shoe relatively to the tool, said guide being mounted for movement into and out of operative position, in combination, power operated mechanism for operating said guide, said mechanism being constructed and arranged successively to advance said guide into its operative position, hold said guide in its operative position for a predetermined period, and retract said guide from its operative position, operator controlled means for starting each stage of operation of said mechanism, and means for automatically stopping the operation of said mechanism at the end of each stage thereof.

8. In a rounding machine, with a rounding tool and a guide for positioning a shoe relatively to the tool, said guide being mounted for movement into and out of operative position, in combination, power operated mechanism for operating said guide comprising a cam having rising and falling slopes and a concentric face between said slopes, said cam being operable in successive stages to cause said guide to be advanced into operative position, held therein, and retracted therefrom by said rising slope, concentric face, and falling slope respectively, operator controlled means for starting each stage of operation of said cam, and means for automatically stopping the operation of said cam at the end of each stage thereof.

9. In a rounding machine, with a rounding tool,

a guide for positioning a shoe relatively to the tool, said guide being mounted for movement into and out of operative position, said guide also being mounted to rotate about an axis with respect to which its work engaging surface is eccentric, and a latch for releasably holding said guide against rotation about said axis, in combination, power operated mechanism for operating said guide, said mechanism being operable in successive stages first to advance said guide into operative position, then to hold said guide in its operative position, and finally to retract said guide from its operative position, means constructed and arranged to release said latch from said guide while said guide is held in its operative position, operator controlled means for starting each stage of operation of said mechanism, and means for automatically stopping the operation of said mechanism at the end of each stage thereof.

10. In a rounding machine, with a rounding tool, a guide for positioning a shoe relatively to the tool, said guide being mounted for movement into and out of operative position, said guide also being mounted to rotate about an axis with respect to which its work engaging surface is eccentric, and a latch for releasably holding said guide against rotation about said axis, in combination, power operated mechanism for operating said guide comprising a cam having rising and falling slopes and a concentric face between said slopes, said cam being operable in successive stages to cause said guide to be advanced into operative position, held therein, and retracted therefrom by said rising slope, concentric face, and falling slope respectively, operating means for said latch, a member carried by said cam for actuating said latch operating means while said guide is held in its operative position, operator controlled means for starting each stage of operation of said cam, and means for stopping the operation of said cam at the end of each stage thereof.
